DESIGN FOR A HANDLE FOR SPOONS, FORKS, OR SIMILAR ARTICLES.

SPECIFICATION forming part of Design No. 35,556, dated January 7, 1902.

Application filed December 12, 1901. Serial No. 85,704. Term of patent 7 years.

To all whom it may concern:

Be it known that I, WILLIAM C. CODMAN, a subject of the King of Great Britain, residing at Providence, in the county of Providence and State of Rhode Island, have invented and produced a new and original Design for the Handle of a Spoon, Fork, or Similar Article, of which the following is a specification, reference being had to the accompanying drawings, forming part thereof.

Figure 1 is a plan view of the front of the handle, and Fig. 2 a view of the rear of the same. The tines of a fork are indicated in broken lines in both figures.

The leading or material feature of my design consists of the raised marginal edges of the handle, representing rods bound together at intervals, forming the conventional symbol of union. The ends of these raised margins terminate in foliated scrolls, surmounted at the upper end with a crest. On the front of the handle a marshal's staff surrounded by a spirally-wound ribbon terminates in the representation of the head of an ox. A horn of plenty with fruit is suspended from the conventional United States shield, surmounted by an eagle. The head of a man inclosed between an olive and a palm branch ornaments the upper part of the front of the handle. On the rear the panel between the raised margins is ornamented at the stem with a reversed torch and the rest of the panel with a palm-branch, surrounded with a crown and a spirally-disposed ribbon. The front of the handle represents, symbolically, power, and the rear represents sorrow.

Having described my invention, what I claim as new, and desire to secure by Letters Patent, is—

The design for the handle of a spoon, fork or similar article, as herein shown and described.

In testimony whereof I have signed my name to this specification in the presence of two subscribing witnesses.

WILLIAM C. CODMAN.
